HEAD BALLAST BLOWING VALVE MECHANISM FOR AUTOMOBILE TORPEDOES

Lewis Jones, deceased, late of Upwey, Weymouth, England, by William Thomas Wilkinson, executor, Weymouth, England, assignor to Vickers-Armstrongs Limited, London, England, a company of Great Britain

Application October 10, 1946, Serial No. 702,397
In Great Britain July 26, 1938

1 Claim. (Cl. 137—685)

1

This invention relates to head ballast blowing mechanism for automobile torpedoes of the kind described in British patent specification No. 398,578 which involves the use of a movable flap which, when in the rearward position it assumes under the pressure produced by the movement of the torpedo through the water, serves to hold a diaphragm of the hydrostatic device against inward movement and only liberates it when the said movable flap moves forward as a result of the diminution of the pressure thereon when the torpedo loses speed, the diaphragm then being free to move inwards to open an air valve admitting compressed air to blow out water or other liquid ballast from the practice head to cause the torpedo to rise to the surface.

It has been found that this known construction of air valve suffers from the disadvantage that the valve operating lever occasionally fails to hook itself under the retaining catch provided therefor, owing to insufficient opening of the valve, this insufficient opening being occasioned when the torpedo has only a small negative buoyancy at the end of its travel or fails to stop quickly and continues to paddle along.

Sufficient water or ballast will be blown from the torpedo upon the opening of the valve to enable the torpedo to become buoyant and float on the surface, but the pressure on the outside of the valve will then be decreased and if the valve is not retained in the open position it will close and prevent any more air escaping into the head, the engine and heater of the torpedo will gradually fill with water and the result may be that the torpedo having a few pounds positive buoyancy will float away, and as it may have very little buoyancy it will be practically invisible and thus may be lost.

The object of the present invention is to overcome the above disadvantage and the invention accordingly consists in providing a plunger adapted to co-operate with an extension of the valve operating lever in such a manner that it forces the lever into operative contact with its retaining catch immediately the valve is opened.

In order that the said invention may be clearly understood and readily carried into effect, the same will now be described with reference to the accompanying drawing which is a view in cross section similar to Figure 4 of specification No. 398,578.

Referring now to the drawing, a cylindrical chamber L is formed in the body H and is in

5 communication with a passage G communicating via the air valve D with the compressed air supply conduit M leading from a suitable source of supply of compressed air, the chamber L also communicating with an outlet passage B leading into the torpedo head. A plunger A suitably guided in the body H, is fitted with a piston C which is adapted to reciprocate in the chamber L, this piston being much larger in area than the cross-sectional area of the passages G and B. The upper end of the plunger A, when the valve D is closed has a very slight clearance from an adjustable abutment, such as screw K⁵ of the valve operating lever K, and an adjustable abutment N in this lever at the same time has a very slight clearance from the stem D¹ of the valve D, so that when the valve D is closed by its spring D² this spring does not load the plunger A. The catch K⁴ in the non-locking position shown in the drawing is normally pressed against the adjacent extremity of the lever K by a spring K⁷.

20 The passage G from the operating valve D of the mechanism is in permanent communication with the portion of the cylinder L below the piston C and in the normal position of the piston C, i. e. the position of rest, the outlet E to the passage B leading into the torpedo head is closed by the piston. A small hole F is drilled 25 from the top of the cylinder L to passage B to provide the small degree of yield to the displacement of air above the piston C to prevent a too sudden displacement of the piston C, i. e. to contribute towards the necessary build-up of 30 air pressure beneath the piston, whilst at the same time releasing air above the piston at the required rate into the conduit B. Thus, in effect, a form of yielding air cushion is provided 35 above the piston C.

40 The abutment K⁵ formed on the valve operating lever K is on the opposite side of the pivotal point K¹ of the lever to that of a hook end K⁶ which co-operates with the retaining catch K⁴.

45 From the above, it will be seen that immediately the valve D is opened, and prior to the hook end K⁶ of the lever K engaging under the retaining catch K⁴, compressed air will flow into the part of the chamber L beneath the piston C and 50 be unable to escape quickly enough to avoid a pressure being built up. This pressure will force the piston C and plunger A upwards to the limit of their travel and the plunger impinging on the extension K⁵ of the valve lever K, will knock this end of the lever in the upward direction about

its pivotal point K¹ and suddenly drive the hook end K⁶ downwards and into retaining engagement with the retaining catch K⁴. The lever K also co-operates with a lever K² as described in the previously mentioned prior British specification No. 398,578, the lever K² abutting upwards against an adjustable abutment screw K⁸ in the lever K and by reason of hydrostatic pressure applied to a paddle (not shown) during the movement of the torpedo through the water urging the end K⁶ of the lever K downwards to partially open the valve D, the lever K thereupon becomes locked by the catch K⁴. However, the principal purpose of the piston is to actuate the lever K in such manner that in moving to effect latching the end K⁶ of the lever under the catch K⁴, the initial or partial opening of the valve D releases air pressure to the piston C which is driven upwards so that it knocks the valve D fully open as soon as even only a slight air pressure is passed through. That is to say, it anticipates the increase of hydraulic pressure on the main mechanism to positively lock the valve D open.

In this manner it will be easily seen that the valve D is retained in the open position until the head is completely blown, thus avoiding the disadvantages set out in the opening paragraphs of the specification.

What is claimed is:

In governing mechanism for head ballast blowing mechanism for a torpedo of the type in which there is provided an air valve and a lever which is operated from hydrostatically responsive means to produce an opening movement of the said air valve, and further has combined with it means to lock it in the position in which it maintains the air valve opened, the provision of a cylinder, an inlet to the cylinder, a compressed air passage leading from said inlet and adapted to be connected to a source of air pressure via the

said valve, an outlet in said cylinder from which extends a passage for discharging the compressed air, a piston in the cylinder permanently exposed at one side to said inlet and compressed air passage and on its other side permanently isolated from said compressed air passage but having communication with said passage leading from said outlet to afford an air cushion yieldingly opposing the displacement of the said piston by the initial air pressure flowing via said valve, an extension from said piston having driving connection to said lever, operating means extending between said valve and lever, said piston normally isolating the said inlet from the said outlet and adapted to be displaced by the air pressure fed along said passage consequent upon initiation of the opening movement of said valve so as to supplement the initially applied valve opening movement of the lever and complete the valve opening movement of the lever, and to establish communication between the said inlet and outlet, and a spring loaded catch adapted to trip over and retain said lever in the valve-full-open position.

WILLIAM THOMAS WILKINSON:
Executor of the Estate of Lewis Jones, deceased.
